MATERIAL IMPELLING FAN

James L. Wall, Washington, Ga., assignor of one-third to Claude Norman Jackson, Washington, Ga.

Application July 8, 1943, Serial No. 493,894

8 Claims. (CL 302—37)

This invention relates to an improved material impelling fan.

More particularly, the invention relates to an improved fan construction adapted for installation in planer mills, saw mills, or the like for operation as a pneumatic conveyor for impelling waste material from one point to another through the medium of a continuous blast of air.

A primary object of the invention is the provision of a fan for impelling material from one position to another, and is so constructed as to preclude contact of the material with the blades of the fan while being impelled therethrough.

A further object of the invention is the provision of a material impelling fan for drawing material from one position through the fan to another position, the fan being formed to segregate the material and direct it out of range of the fan blades while air from the inlet of the fan is directed to the center thereof for maintaining the material out of range of the fan blades while being impelled through the fan.

A still further object of the invention is the provision of a material impelling fan which is of marked simplicity in construction and is capable of ready installation as a pneumatic conveyor for waste material as saw dust or shavings as well as for other materials, such as cotton seed, grains, sand, etc.

For a more complete understanding of the nature and objects of the invention, reference will be had to the following detailed description, taken in connection with the accompanying drawings, wherein—

Figure 1 is a vertical section taken in the plane of line 1—1, Fig. 2, with certain broken away parts shown in dot-and-dash outline.

Fig. 2 is a section taken in the plane of line 2—2, Fig. 1, with the bearing support being observed in the vertical plane of line 2—X.

Fig. 3 is an elevational view of the fan on a reduced scale particularly illustrating the adaptability thereof for attachment in angular positions.

Fig. 4 is an end view of the fan intake portion.

Fig. 5 is a section in the plane of line 5—5, Fig. 1.

Fig. 6 is a partial transverse section in the plane of line 6—6, Fig. 1.

Fig. 7 is a partial transverse section in the plane of line 7—7, Fig. 1.

Referring now in detail to the drawings by use of reference characters, 10 designates the main portion of the fan casing or housing. The main housing portion includes an inlet portion 11 and

an exhaust portion 12. The housing further includes a removable side plate 13 retained in position by a ring 13' removably secured to the main portion.

5 Unitary with or rigidly secured to the plate 13 is an air deflector in the form of a curved conduit 14. The deflector conduit 14 at one end thereof opens into the center of plate 13 co-axially with the fan shaft later to be described, and the other end thereof opens into the lower arcuate portion 15 of the intake 11.

The peripheral portion of the housing includes an arcuate wall 16 which, as indicated at 17, terminates at the advance wall of the conduit 14, 15 and the peripheral portion further includes an arcuate wall 18 which terminates substantially beyond the point 17, as indicated at 19.

The walls 16 and 18 are concentric, but the former is of greater radius than the latter, thereby providing a material inlet passage 20 separated from the air inlet to conduit 14 by the wall 16.

A suitable support 21 is provided and which preferably includes legs 22 in each of which is supported a bearing 23 for the fan shaft 24 which 25 extends through an aperture 25 in the fan housing to the interior thereof. A pulley 24a is preferably secured to shaft 24 for driving same.

A union coupling 26 is preferably provided for effecting separation of the housing and support or relative adjustment thereof rotatively of shaft 24. Secured to the inner end of the shaft 24 is the hub 27 of a fan embodying a plurality of spokes 28, to each of which is secured a blade 29.

As is more clearly shown in Fig. 1, the blades 35 28 are concave in the direction of rotation thereof and have their convex sides substantially tangent to the centers of the spokes, although the outer edges of the blades are substantially in advance of their inner edges.

40 The blades as indicated in Fig. 2 are substantially of the internal width of the housing, and as seen in Fig. 1, the outer edges of the blades are in closely spaced relation to the wall 18 but are substantially spaced from the wall 16 for a purpose later to appear. The wall 18 is preferably of greater extent than the spacing between two blades.

The housing inlet 11 is preferably tubular at its free end, as indicated in Fig. 4, for connection with a tubular conduit, and since it is essential that the outer wall of the inlet be flat in conformity with the wall 18 for proper distribution of the material, the inlet gradually merges from the tubular form at its free end through the forms indicated at 11a, 11b, and 11c in Figs. 5,

6, and 7, respectively, the inner wall of Fig. 5 being flat in conformity with the adjacent end of the conduit 14.

The operation of the improved fan construction is as follows: The fan blades 29 are revolved in a counter-clockwise direction, air and solids being handled are drawn into the intake 11 and forced out of the exhaust 12 by the air pressure developed by the rotating blades.

The travel of the air is in the direction shown by arrows A, Figs. 1 and 2, and the direction of travel of the solids is in the direction shown by arrows S. Thus, it will be seen that the admixture of air and solids is drawn into the intake 11 and, by means of the lower curved form of the intake, the solids are segregated, but due to their momentum under the action of the air current they are directed into the passage 28 while the air enters the deflecting conduit 14 and is admitted to the center of the fan, wherefrom it is directed outwardly by the arcuate blades, as indicated by arrows in Fig. 1, for impelling as well as maintaining the solids beyond the outer edges of the blades 29, from which they are discharged through the outlet 12.

By means of the union coupling 26 the fan may be supported vertically as in Figs. 1 and 2 or angularly as in Fig. 3, thereby adapting the fan for installation in various positions.

The characteristic feature of my invention is the provision of a material impelling fan embodying a casing or housing including a fan enclosing portion, intake and exhaust portions, and solid material segregating and air deflecting portions, whereby the solids drawn into the intake portion in air suspension are segregated for passage through the fan-enclosing portion outwardly of the outer edges of the fan blades, while the major volume of air admitted through the intake portion is deflected through the conduit 14 to the axial center of the fan. The particular arcuate form of the fan blades provides for deflection of the air from the center of the fan or housing outwardly and circumferentially of the fan enclosing portion of the housing, whereby the solids are maintained adjacent the wall 16 as well as circumferentially impelled through the housing from the inlet passage 28 to the exhaust 12.

While I appreciate the fact that fans have heretofore been proposed for maintaining solids out of contact with the fan blades during passage therethrough, nevertheless the structure herein disclosed provides for maximum efficiency in this respect with a minimum of cooperating structural elements, and the fan is fully capable of use with waste solids such as saw dust or shavings as well as with solids, such as various grains, sand, and the like.

While I have disclosed but a single specific embodiment of my invention, such is to be considered as illustrative only, and not restrictive, the scope of the invention being defined in the subjoined claims.

What I claim and desire to secure by U. S. Letters Patent is:

1. A material impelling fan construction comprising a housing including a fan enclosing portion and inlet and exhaust portions communicating therewith, the fan enclosing housing portion having side walls and an arcuate peripheral wall, a fan rotatably supported within the fan enclosing housing portion and including blades whose outer ends are in substantial spaced relation to said peripheral wall, an air deflecting conduit communicating with said intake housing portion

and with said fan enclosing housing portion centrally of the fan, and a material inlet passage between said intake housing portion and said fan enclosing housing portion immediately within said arcuate peripheral wall for admitting solids within said arcuate wall, the air admitted at the center of the fan being directed outwardly thereby for impelling the solids through the fan enclosing housing portion and maintaining same out of range of the fan blades.

2. A fan construction for impelling solids from one position to another comprising a housing including a fan enclosing portion having an arcuate peripheral wall of substantial circumferential extent and having a free end, the fan enclosing housing portion further including a relatively short arcuate peripheral wall radially inwardly of said first arcuate wall and having a free end portion lapping the free end of the first wall in the provision of a solids inlet passage to the fan enclosing housing portion, the said arcuate walls merging into an exhaust housing portion, the housing further including an inlet portion in communication with said passage, a fan rotatably supported within said fan enclosing housing portion, and an air deflecting conduit communicating with said inlet housing portion and the fan enclosing housing portion at the center of the fan.

3. A fan construction according to claim 2, wherein said solids inlet passage is spaced radially inwardly of the end of said air deflecting conduit in communication with said inlet housing portion and separated therefrom by the free end portion of said first arcuate wall.

4. A fan construction for impelling solids from one position to another, comprising a housing including a fan enclosing portion and inlet and exhaust portions, the first portion including laterally spaced side walls and arcuate peripheral walls, a fan rotatably supported in the first portion concentric with said peripheral walls, the exhaust portion being in communication with said first portion, the said peripheral walls being radially spaced for providing a solids inlet passage to the first portion and being in communication with the inlet portion, and an air deflecting conduit communicating at one end thereof with the first portion at the center of the fan and communicating at the other end thereof with the inlet portion radially outwardly of the solids inlet passage and separated therefrom by the outermost one of said peripheral walls, the said inlet portion merging into the innermost of said arcuate walls through an arcuate bottom wall portion below the communicating end of said air deflecting conduit for collecting the solids and deflecting same into said inlet passage.

5. A fan construction for impelling solids from one position to another, comprising a housing including a fan enclosing portion and inlet and exhaust portions, the first portion including laterally spaced side walls and arcuate peripheral walls, a fan rotatably supported in the first portion concentric with said peripheral walls, the exhaust portion being in communication with said first portion, the said peripheral walls being radially spaced for providing a solids inlet passage to the first portion and being in communication with the inlet portion, and an air deflecting conduit communicating at one end thereof with the first portion at the center of the fan and communicating at the other end thereof with the inlet portion radially outwardly of the solids inlet passage and separated therefrom by the outer-

most one of said peripheral walls, one of said side walls being removably attached to said housing, and said air deflecting conduit being rigidly supported by the removable side wall.

6. A fan construction for impelling solids from one position to another, comprising a housing including a fan enclosing portion and inlet and exhaust portions, the first portion including laterally spaced side walls and arcuate peripheral walls, a fan rotatably supported in the first portion concentric with said peripheral walls, the exhaust portion being in communication with said first portion, the said peripheral walls being radially spaced for providing a solids inlet passage to the first portion and being in communication with the inlet portion, and an air deflecting conduit communicating at one end thereof with the first portion at the center of the fan and communicating at the other end thereof with the inlet portion radially outwardly of the solids inlet passage and separated therefrom by the outermost one of said peripheral walls, said fan including circumferentially spaced blades with the outer edges thereof substantially spaced from the outermost of said arcuate walls and in closely spaced relation to the innermost of said arcuate walls, and the circumferential extent of the innermost of said arcuate walls being substantially less than that of the outermost and being slightly greater than the circumferential spacing of the outer edges of the fan blades.

7. A fan construction for impelling solids from one position to another, comprising a housing including a fan enclosing portion and inlet and exhaust portions, the first portion including laterally spaced side walls and arcuate peripheral walls, a fan rotatably supported in the first portion concentric with said peripheral walls, the exhaust portion being in communication with said first portion, the said peripheral walls being

radially spaced for providing a solids inlet passage to the first portion and being in communication with the inlet portion, and an air deflecting conduit communicating at one end thereof with the first portion at the center of the fan and communicating at the other end thereof with the inlet portion radially outwardly of the solids inlet passage and separated therefrom by the outermost one of said peripheral walls, said fan comprising a hub portion, spokes radiating from the hub portion, and arcuate blades substantially rectangular in plan secured to said spokes, said blades having their concave portions disposed in the direction of rotation of the fan and their outer edges circumferentially in advance of their inner edges.

8. A fan construction for impelling solids from one position to another, comprising a housing including a fan enclosing portion and inlet and exhaust portions, the first portion including laterally spaced side walls and arcuate peripheral walls, a fan rotatably supported in the first portion concentric with said peripheral walls, the exhaust portion being in communication with said first portion, the said peripheral walls being radially spaced for providing a solids inlet passage to the first portion and being in communication with the inlet portion, and an air deflecting conduit communicating at one end thereof with the first portion at the center of the fan and communicating at the other end thereof with the inlet portion radially outwardly of the solids inlet passage and separated therefrom by the outermost one of said peripheral walls, said inlet portion being tubular at its free end, the arcuate wall of the inlet portion merging into a flat wall which in turn merges into the innermost of said arcuate peripheral walls.

JAMES L. WALL.
